UNITED STATES PATENT OFFICE

CARL GUSTAV THORBJÖRN SALENIUS, OF GOTENBORG, SWEDEN

WASHING MACHINE

Application filed October 14, 1927, Serial No. 226,216, and in Germany October 21, 1926.

This invention relates to improvements in machines for washing clothes of the type having a spherical washing drum adapted to rotate around a horizontal axis and having 5 no outer jacket.

All known machines for washing clothes have the disadvantage, that, when they are operated by hand, their operation fatigues the operator in a comparatively short time.

10 When the machine is driven by a motor, its construction is so complicated, that the initial cost and the cost of the operation are exorbitant for a normal household. Furthermore, many of the washing machines on 15 the market are difficult to clean, so that the soap and dirt particles remaining in the corners of the drum dry and become solid and are dissolved only with the next wash and adhere to the clothes as dirt flocks.

20 Another drawback of the known washing machines having a closed washing drum resides in the fact, that a pressure above atmospheric is generated in the drum, due to the heat of the supplied hot water becoming 25 free when the drum is agitated, and heating the air above the washing water, which air expands and produces a pressure above atmospheric. This drawback is still increased, when the drum is heated during operation, 30 for example, by electricity. Furthermore, the said pressure above atmospheric is also produced when carbonic acid is generated in the drum by the use of one of the known washing powders. This pressure requires 35 that the drum cover be fastened to the drum in a tight and reliable manner. When the machine is not fitted with a reliable fastener, for the drum cover a fastener may break off, 40 releasing the cover which is blown away, and thereby permitting the soapy water to escape.

Now the invention has for its object to eliminate these drawbacks and to so simplify the construction of washing machines 45 of the character stated, that the first costs of the machine as well as those for its main- tainance and attendance are so low, that the machine may be used also in small households.

50 In order that the invention can be more

easily understood, some preferred embodiments of the same are illustrated in the drawings which accompany and form part of this specification. In all these embodiments the washing drum has a spherical shape, as 55 this shape has no corners. A drum of this shape is the easiest to manufacture and to mount on the machine frame.

Fig. 1 is a sectional view of a washing machine embodying my invention. 60

Fig. 2 is a top view of the machine shown in Fig. 1, with part of the caging broken away.

Fig. 3 shows a washing machine embodying my invention with a modified form of 65 driving means.

Fig. 4 is a sectional view of part of drum body and lid of a washing machine, showing a modified form of connection between the 70 two.

Fig. 5 shows a sectional view of one of the trunnions of the drum and a modification of the pressure equalizer shown in Fig. 1.

Fig. 6 is a view on a larger scale of the 75 pressure equalizer which is shown in Fig. 1.

Coming now to a description of my invention, a drum 10 is mounted for rotation on a horizontal ring 12 of profile iron by means of trunnions 11. The ring 12 rests on feet 13 which are interconnected by bracing bars 14. An electric motor 15 is mounted on one of these bars 14 and is completely enclosed in a housing along with a suitable transmission gear. The latter has a rope pulley 16 for a driving cord 17. In contradistinction to some washing machines the drum itself serves as the driving pulley. To prevent the cord gliding off from the pulley 16, the drum 10 is provided with a ring 18 80 that guides the cord 17. The cover 19 of the drum has the shape of a spherical segment and is preferably provided with an outer stiffening frame 20. By means of bolts 21 pivoted on a ring 22 fixed on the drum 10, 95 the cover 19 may be tightened thereon through the intermediary of a packing ring 23.

To cause the clothes to be continually agitated and lifted in the drum and to glide 100

down from their highest position, web-like drivers 24 may be provided in the drum.

When the drum is filled with the clothes to be cleaned and with the washing liquid and washing powder, the cover 19 is put on the drum and tightened. Then the motor 15 is started which rotates the washing drum at the required rate of revolutions, whereby the clothes are washed. To facilitate still more the cleaning of the drum, the drivers 24 may be designed so as to be removable. In every case, however, the cleaning of the drum is very easy, as no protruding members exist in the interior of the drum, except the two drivers 24, and, consequently, the cleaning is executed more carefully than with the known washing machines.

Instead of being driven from the motor 15 by means of the cord 17, the drum may also be rotated by means of toothed or friction gears 27, 26, as shown in Fig. 3. In this case the larger wheel 26 is arranged on the drum 10 in the form of a friction ring, while a second disk 27 is connected to the transmission gear of the motor 15. To permanently and uniformly hold in engagement said two disks, the electric motor 15 is rockably mounted by means of trunnions 29 in a bracket 28 mounted on the frame bar 14, and is so under the action of a spring 30, that the disk 27 is permanently pressed against the disk 26. When the drum is driven by a cord 17, the motor 15 of course may be rockably mounted in the conventional manner, so as to tighten the cord 17.

The cover may be fastened to the drum by screws and wing nuts 31, as shown in Fig. 3, instead of the described bolts. In order to do away with the massive rings 20 and 22 at the point of closure, the cover 19 may be stiffened by providing on it a U-shaped pressed circular edge 32, as illustrated in Fig. 4, and the edge 33 of the aperture of the drum may be designed in a similar manner, so that the two U-shaped edges engage each other. A packing ring 34 may be interposed, while the tight connection between cover and drum is secured by hooks and shackles 35.

In order to prevent, when the drum is rotating, the clothes which may happen to be in the neighbourhood of the machine or the dress of the operator from being caught by the rotating drum, in particular, by the latter's protruding closure means, and the operator himself from being hurt, a protective cap may be put on the drum. This cap is advantageously supported by the ring 12 of the frame and may consist of semi-circular bars 37 fixed on a ring 36. The latter engages ring 12, as shown in Figs. 1 and 2. A hemispherical wire basket 38 is placed over the bars 37.

The above-mentioned pressure which prevails in the drum is eliminated in the following manner. As it is impossible to provide an opening in the drum wall, through which

the washing liquid can escape, and as check valves cannot be used, a passage 39, see Fig. 5, is provided in one of the trunnions 11 or in both of them. This passage is preferably formed by a small pipe having projecting ends 39^a and 39^b, as shown, to prevent the washing liquid trickling down on the inside drum wall from entering the pipe 39 and to permit the liquid which enters the pipe to drop off easily on the outside. As the clothes may be easily caught by the inner projecting pipe end 39^a, this end is preferably covered with a perforated protective cap 40. In this way the pressure can always escape uniformly through the passage, so that a substantially atmospheric pressure is maintained in the drum and special precaution measures are superfluous as to the tightening of cover 19 and the closure means.

When the small liquid quantities that escape through pipe 39 are to be collected, a spout 41 may be arranged on the ring 12 of the machine frame and a small bucket 42 or the like may be hung on the spout.

The pressure control passage may be of the form shown in Figs. 1 and 6. In this case the small tube 39 is bent to a Z-shape and is so fixed on the drum wall, that its inner end 39^a projects radially, while its outer end 39^b passes through the drum wall and opens on the outside thereof. The inner end in this case is also covered by a perforated protective cap 40.

What I claim and desire to secure by Letters Patent, is:—

In a machine of the class described, a frame, a spherical washing drum mounted for rotation around a horizontal axis on said frame, a motor, an annular flange on said drum arranged in a plane at right angles to the rotating axis of said drum and between the greatest circumference of the drum and one of the drum's trunnions, and a belt engaging said flange and said drum and adapted to be driven by said motor.

In testimony whereof the foregoing specification is signed.

CARL GUSTAV THORBJÖRN SALENIUS.
